(57) **CLAIM**

The ornamental design for a display screen with animated graphical user interface, as shown and described.

DESCRIPTION

The patent or application file contains at least one drawing executed in color. Copies of this patent or patent application with color drawings(s) will be provided by the Office upon request and payment of the necessary fee.

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the first image in a sequence for a display screen with animated graphical user interface showing an alternative embodiment of the design in FIGS. 1-12 claiming color;

FIG. 14 is the second image thereof;

FIG. 15 is the third image thereof;

FIG. 16 is the fourth image thereof;

FIG. 17 is the fifth image thereof;

FIG. 18 is the sixth image thereof;

FIG. 19 is the seventh image thereof;

FIG. 20 is the eighth image thereof;

FIG. 21 is the ninth image thereof;

FIG. 22 is the tenth image thereof;

FIG. 23 is the eleventh image thereof;

FIG. 24 is the twelfth image thereof;

FIG. 25 is the first image in a sequence for a display screen with animated graphical user interface showing an alternative embodiment of our new design;

(Continued)

FIG. 26 is the second image thereof;
 FIG. 27 is the third image thereof;
 FIG. 28 is the fourth image thereof;
 FIG. 29 is the fifth image thereof;
 FIG. 30 is the sixth image thereof;
 FIG. 31 is the seventh image thereof;
 FIG. 32 is the eighth image thereof;
 FIG. 33 is the ninth image thereof;
 FIG. 34 is the tenth image thereof;
 FIG. 35 is the eleventh image thereof;
 FIG. 36 is the twelfth image thereof;
 FIG. 37 is the first image in a sequence for a display screen with animated graphical user interface showing an alternative embodiment of the design in FIGS. 25-36 claiming color;
 FIG. 38 is the second image thereof;
 FIG. 39 is the third image thereof;
 FIG. 40 is the fourth image thereof;
 FIG. 41 is the fifth image thereof;
 FIG. 42 is the sixth image thereof;
 FIG. 43 is the seventh image thereof;
 FIG. 44 is the eighth image thereof;
 FIG. 45 is the ninth image thereof;
 FIG. 46 is the tenth image thereof;
 FIG. 47 is the eleventh image thereof; and,
 FIG. 48 is the twelfth image thereof.
 The appearance of the animated graphical user interface sequentially transitions between the images shown in FIGS. 1-12, 13-24, 25-36 and 37-48, respectively. The process or period in which one image transitions to another forms no part of the claimed design. The broken line showing of the remainder of the user interface and the remainder of the display screen is for environmental purposes only and forms no part of the claimed design.
